CLAIM

The ornamental design for a badge for a golf club head, as shown and described.

DESCRIPTION

FIG. 1 is a top perspective view of a badge for a golf club head;

FIG. 2 is a bottom perspective view of the badge of FIG. 1; FIG. 3 is a front view of the badge of FIG. 1;

FIG. 4 is a rear view of the badge of FIG. 1;

FIG. 5 is a top view of the badge of FIG. 1;

FIG. 6 is a bottom view of the badge of FIG. 1;

FIG. 7 is a left view of the badge of FIG. 1; and,

FIG. 8 is a right view of the badge of FIG. 1.

The broken lines shown in one or more of the figures are for illustrative purposes only and form no part of the claimed design.

1 Claim, 3 Drawing Sheets
